[57] ABSTRACT

A device for emergency escaping device for high building comprising a integral of vertically serial protection piping frames having a plurality of cross plates or pipes spacedly opposed to the exterior wall of the building, a plurality of poles in forward and backward rows in alignment, a plurality of stepping plates and resting plate secured to the exits of the every other floor of the building and the protection piping frame in other levels of said stepping plate, respectively, whereby peoples can escape safely sliding down with a certain pose at every stepping plate and resting plate.

5 Claims, 3 Drawing Figures

FIG. 2

FIG. 1

PATENTED NOV 19 1974

3,848,698

SHEET 2 OF 2

FIG. 3

EMERGENCY ESCAPING DEVICE FOR HIGH BUILDING

BACKGROUND OF THE INVENTION

1. Field of the Invention

This invention relates to an emergency escaping device for high building.

2. Description of the prior arts

When fires and other emergency events are break out in the high buildings, the peoples can not use the elevators and staircases, because the fires and smokes come up from downstairs when the lower floors are in fires.

Even when the exterior staircases and escaping shooting tubes are quipped at the building, it is not enough to admit the peoples to escape safely, since many peoples rush to escape from the limited escaping equipment, and sometimes it causes a bigger damage.

Furthermore, when the peoples escape sliding down the vertical conduits, bars, and ropes from the high building, it is often found that they dishold those equipment before arriving at the ground, since they feel the abrasive heat at their hands and are tired to hold said equipment, whereby they receive severely sad injuries and they are often caused to be died.

When the fire-cars having extension ladders arrives at the site, within the earlier time of the fire broken out, those are useful for escaping peoples, however, when they arrive in late, those are often useless to save peoples and sometimes the length of the ladders are not enough to reach the higher floors of the building and the absolute numbers are in short to save many peoples.

Therefore, it is a very difficult to save peoples in the high building when the fires and other emergencies happen.

As mentioned above, saving peoples in the high building and escaping those when the emergencies, particularly fires break out, are very difficult as always confronting with the danger and difficulty inspite of the long and constant study of preventing the fire, escaping, and saving peoples.

Up to now, complete and cost-saving devices are not found yet.

Therefore, this invention intends to provide a relatively cost-saving emergency escaping for high building which admits that many peoples can escape safely.

An emergency escaping device for high building of this invention comprises an integral of vertically serial protection piping frames having a plurality of cross plates or pipes, said frames being faced apart with the emergency exits of the building and building exterior wall and being also used as the emergency escaping ladders; a plurality of poles within said protection piping frames for which peoples escape sliding down, said poles being aligned in two rows in forward and backward seeing from said protection piping frames; a plurality of stepping plates being located at the every other emergency exit at the building floors, said stepping plate being equipped with said several poles in the backward position therethrough spaced at a proper distance from the several poles in the forward position; and a plurality of resting plates being located at protecting piping frames at the same level with every other floors in different from foregoing floors having said stepping plates, said resting plates being equipped with several poles therethrough spaced at a proper distance from the backward poles.

One object of this invention is to provide an emergency escaping device to permit the peoples to escape safely without falling down to the ground.

Another object of this invention is to provide an emergency escaping device to admit everyone to use without afraid and fear.

Still further object of this invention is to provide the emergency escaping device to admit many peoples to be able to escape within a short time.

Still further object of this invention is to provide the emergency escaping device to admit the peoples in physical inferiority to be able to escape safely with help by the escorts.

Still further object of this invention is to provide the emergency escaping device in order that the peoples can escape without special operation and training required at normal time.

Still further object of this invention is to provide the emergency escaping device which is applicable to a skyscraper such as in 100 floors and the surrounding protection piping frames are usable as ladders.

Still another object of this invention is to provide the emergency escaping device which is easily installed with a reasonable cost.

BRIEF DESCRIPTION OF THE DRAWING

FIG. 1 is a front elevational view of the emergency escaping device according to this invention mounted on the exterior wall of the building.

FIG. 2 is a view showing the escaper can escape from the building utilizing the emergency escaping device according to this invention, and

FIG. 3 is a partial perspective view of the building equipped with the escaping device according to this invention.

Now, the preferred embodiment of this invention is hereinafter described with reference to the accompanied drawing.

An integral of the protection piping frames 3 also useable as escaping ladders is located spaced apart at a proper distance, facing with the emergency exits 1₂, 1₃ . . . 1_n, from the exterior wall of the high building to which roof said protection frames are secured at their curved upper portion. Several vertical poles 4 and 5 for sliding down are quipped in two rows in forward and backward alignments inner the surrounding protection piping frame 3.

A plurality of stepping plates 6₃, 6₅, 6₇, 6₉ . . . are securely mounted into the every other emergency exit 1₃, 1₅, 1₇, 1₉ of the floors at each one end at a right angle with the exterior wall, while a plurality of resting plates 7₂, 7₄, 7₆, 7₈ . . . are securely mounted on the protection piping frames therein at a right angle at the same levels of the every other emergency exit in different with the abovementioned floors having said stepping plates. Said stepping plates 6₃, 6₅, 6₇, 6₉ . . . are spaced at a proper distance from the several poles 4 surrounded within the protection frames 3, and through which plates several poles 5 are passing from the top into the ground. Said resting plates 7₂, 7₄, 7₆, 7₈ are equipped with several poles 4 passing therethrough from the top into the ground which are spaced at a proper distance from said several rods 5.

Thus, in escaping sequence, as in shown in FIG. 2, assuming that one, A in seventh floor (7F) escapes, one, A comes out the emergency exit 1₇, then, stepps onto the stepping plate 6₇ thereof, catches one of the vertical

poles 4, and slides down onto the resting plate 6₅ provided on the protection frames opposite to the emergency exit 1₆, then turns to opposite direction, and catches the pole 5 of the backward alignment, and then slides down onto the stepping plate 6₅ provided on the fifth floor. Thereafter, same sequence is applied turning his body in opposite direction so as to grasp the pole in two rows alternately for sliding down onto the stepping plates and/or resting plates until he arrives at the ground.

Said protection piping frames, said stepping and resting plates, and said vertical poles may be made of iron steel and equivalent strong materials coated with unflamable corrosion-free painting.

Furthermore, it is advisable to provide some safety cushioning mat 8 including spring and similar devices on the ground inner the frame 3 so that one receive softened shock if he discatches the pole or one falls down onto the mat on the ground.

As described above, one can slide down the poles 4 and/or 5 onto the stepping plates 6 with odd numbers and resting plates 7 with even numbers one by one whereby one can pose on said plates and one can grasp the poles after certain pose and further, alternatively one can walks down the ladders of plates or pipes provided on the surrounding protection frames 3.

Moreover, when the lower floors were not in fire, one can enter into the building from one of those emergency exits. Therefore, one can escape safer with convenience, than those known in the art, such as poles for sliding down without stepping and resting plates onto the ground without admitting a pose.

Furthermore, said two row poles 4 and 5, stepping plates 6 with odd numbers and resting plates 7 with even numbers are surrounded by the protection piping frames 3 thereby admitting the escaper not to fall down outer the protecting frame 3 and to be received one of the stepping and/or resting plates just below the such place where from one falls down, without falling down onto the ground directly. As is apparent in a foregoing, one can enjoy a very safety escaping from the high building.

In summarizing, two row poles for sliding down in forward and backward position, the stepping plates and the resting plates provided every other floor to each other are surrounded by the protection piping frames which are also usable as ladders by providing cross plate or pipes therewith, so that one can ease his mind of fearing of being on the high place, and one can escape at ease with proper judgement.

The poles 4 and 5 for sliding down are provided in a several numbers in order that many peoples in the building can escape and also the olds and babies, chil-

dren, can escape safely with helps of the escorts.

Therefore, the devices according to this invention provides many effects for safe escaping from the building.

The height of the building is not limited as shown in the preferred embodiment, and it should be understood for those skilled in the art that some modification and alteration shall be made within the scope of the description, the accompanied drawing and claims.

10 I claim:

1. An emergency escaping device for high building comprising

- a. an integral of vertically serial protection piping frames having a plurality of cross plates or arms, said frames being faced apart with the emergency exits of the building and the building exterior wall and being usable as emergency escaping ladders;
- b. a plurality of poles within said protection piping frames for which peoples escape sliding down, said poles being aligned in two rows in forward and backward seeing from said protection piping frames;
- c. a plurality of stepping plates being located at every other emergency exit at the building floors, said stepping plates being provided with said several vertical poles in the backward row therethrough spaced at a proper distance from the several poles in the forward position;
- d. a plurality of resting plates being located at the protection piping frames at the same level with every other floors in different from a foregoing floors having said stepping plates, said resting plates being provided with several poles therethrough spaced at a proper distance from the backward poles.

2. An emergency escaping device according to claim 1, wherein said protection piping frames are curved at its upper portion and secured to the upper roof of the building.

3. An emergency escaping device according to claim 1, wherein said protection piping frames are made of the iron steel piping frame coated with unflamable corrosion-free painting.

4. An emergency escaping device according to claim 1, wherein said stepping and resting plates are made of the iron steel plates coated with unflamable corrosion-free painting.

5. An emergency escaping device according to claim 1, wherein said sliding poles are made of iron steel piping and coated with unflamable corrosion-free paintings.
